UNITED STATES PATENT OFFICE.

NELSON A. HUME, OF BLACK CREEK, NEW YORK.

HOOK.

1,314,963.

Specification of Letters Patent. Patented Sept. 2, 1919.

Application filed November 17, 1917. Serial No. 202,526.

To all whom it may concern:

Be it known that I, NELSON A. HUME, a citizen of the United States, residing at Black Creek, in the county of Allegany and State of New York, have invented certain new and useful Improvements in Hooks; and I do hereby declare the following to be a full, clear, and exact description of the invention, such as will enable others skilled in the art to which it appertains to make and use the same.

This invention relates to improvements in hooks.

The object of this invention is to improve the construction of hooks particularly adapted for doors or the like and the hook has secured thereto a lever which is adapted to move the hook into locking or unlocking position.

A further object of this invention is to provide a lever adapted to be secured to the door or like and has adjustably or pivotally secured thereto a hook whereby the hook may be moved into and out of locking engagement with a staple.

A further object of this invention is to provide a hook having secured thereto a lever and means carried by the hook and lever whereby the lever is limited in its downward movements when the hook is in locking position.

A still further object of this invention is to provide a lever having an attaching plate for facilitating the securing of the same to a door or the like and adjustably and pivotally secured to the lever is a hook which facilitates the movement of the hook into locking engagement with the staple through the medium of its adjustment with relation to the lever.

A further object of this invention is to provide a hook of this character, which will be simple, practical and comparatively inexpensive in construction and one that can be manufactured and sold at a low cost.

With these and other objects in view, the invention consists in the novel combination and arrangement of parts hereinafter more fully described and set forth in the claim hereto appended.

In the drawing

Figure 1 is a front elevation illustrating a fragmentary portion of a door having the hook applied thereto,

Fig. 2 is a front elevation of a fragmentary portion of a door illustrating the appli-

cation of the hook thereto showing the hook in partly open position,

Fig. 3 is a top plan view of the same,

Fig. 4 is a sectional view illustrating the manner in which the hook is adjustably secured to the lever, and

Fig. 5 is a detail sectional view.

Referring to the drawing, the numeral 5 designates the hook in its entirety and it is constructed of metal or other suitable material suitable for the purpose.

The hook comprises a curved shank 6 which has one end curved downwardly and inwardly to provide a bill 7, the opposite end being curved upwardly and apertured.

A curved lever 8 has each of its ends bent laterally at right angles to the shank to provide a manipulating or raising member 9 and a shank engaging member 10. An attaching plate 11 is secured by suitable fastening means 13 to a door or the like as illustrated in the drawing and is pivotally secured as at 14 to the lever 8 adjacent one end thereof. A lug or projection 12 is formed integrally with one end of the lever adjacent its hook engaging end, and this lug or projection is adapted to be movable in the apertured end of the shank 6 of the hook 85 6 is concaved and provided with a plurality of substantially semi-circular concavities 15 which are adapted to engage the rivet or projection 12 so as to permit the hook to be adjustably and pivotally secured to the lever 90 8 as illustrated in Fig. 2 of the drawing.

The manipulating end of the lever 8 has one edge thereof bent laterally and provided with a plurality of upwardly inclined teeth 16 which are adapted to have engagement with the angularly bent portion 17 formed integrally with the upper edge of the hook shank 6 adjacent the bill end thereof, thus it can be seen that the downward movement of the lever with relation to the hook shank will be limited by virtue of engagement of the teeth 16 with the edge of the angularly bent portion 17 formed on the hook shank.

A staple plate is designated by the numeral 19 and when the lever is in the position illustrated in Fig. 1, the rear wall of the bill engages the innermost wall of the staple 19. Thus it can be seen that the door will be held in closed position.

When it is desired to raise the bill 7 from the staple, it is only necessary to grasp the

manipulating end 9 of the lever 8, raise the same upwardly and swing it on its pivot 14 which moves its end 10 in the direction of the staple thus urging the bill 7 away from engagement with the innermost wall of the staple and upon further movement of the lever on its pivot 14 the laterally extending end 10 will engage the under edge of the shank 6 of the hook and raise the same entirely from the staple to permit the door to be opened.

Having thus described my invention, what I claim is:

A device of the character described comprising, a shank, a bill carried by the forward end portion of the shank, a lever hav-

ing its opposite end portions curved, said shank having its rear end portion pivoted to the rear end portion of said lever, a latterally projecting shoulder carried by the forward end of said shank, locking teeth carried by the forward end portion of said lever and adapted for engaging said shoulders, and lugs carried by the opposite ends of said lever.

25

In testimony whereof I affix my signature in presence of two witnesses.

NELSON A. HUME.
